His Attorney

UNITED STATES PATENT OFFICE.

RALPH H. LANGLEY, OF SCHENECTADY, NEW YORK, ASSIGNOR TO GENERAL ELECTRIC COMPANY, A CORPORATION OF NEW YORK.

COIL SYSTEM.

Application filed July 22, 1922. Serial No. 576,767.

To all whom it may concern:

Be it known that I, RALPH H. LANGLEY, a citizen of the United States, residing at Schenectady, county of Schenectady, State of New York, have invented certain new and useful Improvements in Coil Systems, of which the following is a specification.

My present invention relates to inductance coils and supports therefor, and more particularly to coils which may readily be removed from their supports to permit of the convenient interchange of coils having different characteristics.

My invention has particular application in radio apparatus in which it is frequently desired to change the coils employed to permit of the use of the apparatus with a wider range of wave lengths than can be conveniently obtained with a single coil.

20 The object of my invention is to provide a simple and efficient construction which will permit of the ready removal of a coil system comprising, if desired, a fixed and a movable coil, from a holder whereby it may 25 be connected to an electric circuit and the substitution therefor of another coil system having different characteristics.

The novel features which I believe to be characteristic of my invention are set forth 30 with particularity in the appended claims. My invention itself, however, both as to its organization and method of operation will best be understood by reference to the following description taken in connection with 35 the accompanying drawing in which Fig. 1 is a sectional view of one embodiment of my invention; Fig. 2 is a plan view; Fig. 3 is a perspective of the fixed coil; Fig. 4 is an exploded view of the movable coil and its 40 operating mechanism, and Fig. 5 is a perspective of the holder.

As indicated in the drawing, I provide a fixed coil 1 made up of windings 2 and 3, which are wound upon a hollow cylinder 4. Within 45 The terminals of these windings and convenient taps thereon are connected to contact members 5 which are secured to one end of the periphery of the cylinder 4. Within 50 the fixed coil there is mounted a rotatable coil 6, which is supported by trunnions 7 and 8, these trunnions being journaled in the supporting members 9 and 10, which are made of flat strips bent over the end of the cylinder 4 to form contacts 11 and 12.

A holder for the coil system consists of a 55 circular disk 13 having spring contact members 14 secured around its outer edge. Each of the contact members 5, 11 and 12 are provided with projections 15, which engage with the contact members 14 so that when 60 the coil system is inserted in the holder it will be held in its desired position and will not readily slip out or become disengaged. A pin 16 secured to the disk 13 is adapted to engage a slot 17 in the end of the cylinder 4 and insure the placing of the coil system in its desired location in the holder. I have indicated the coil system as mounted in a casing 18, the disk 13 being secured to posts 19 by means of the screws 20 and the posts 70 19 being secured in any desired manner to the bottom of the casing. As a means for rotating the coil 6, I provide a shaft 21 which projects through the casing 18 and is provided with an operating handle 22. The 75 disk 23 which is secured to the end of this shaft is provided with a slot 24. When it is desired to remove or insert a coil system, such as that described, the handle 22 is turned to bring the slot 24 upon the upper 80 side of the disk 23. The trunnion 8 which is connected to the movable coil 6 may then be inserted in the slot 24 or removed therefrom as the coil system is inserted in or removed from the holder. By reason of the 85 engagement of the trunnion 8 with the slot 24 a rotation of the shaft 21 will produce a rotation of the coil 6.

It will be apparent that a coil system such as that described may be connected to any 90 desired electrical circuit by means of conductors connected to the contact members 14 and that by varying the number of taps on the coil windings and the number of contact members employed any desired amount 95 of winding may be included in a circuit. The coil system may be employed merely as a variometer or the movable coil may serve as a variable coupler, as desired.

While I have shown and described the 100 preferred embodiment of my invention, it will be apparent that many variations in the manner of constructing the coil system and in the several structural features whereby the coil system is held in the holder may be 105 made without departing from the scope of my invention as set forth in the appended claims.

What I claim as new and desire to secure by Letters Patent of the United States is:

1. In an apparatus of the class described, the combination of a coil, a hollow cylinder upon which said coil is wound, a plurality of taps to said coil, a plurality of contact members connected to said taps and distributed around the periphery of one end of the cylinder and a holder for said coil having a plurality of contact members arranged in a circle and adapted to make contact with the contact members on the cylinder and thereby serve to hold the coil in a desired position and provide a readily detachable connection between the coil and an electrical circuit.

2. In an apparatus of the class described the combination of a coil, a hollow cylinder upon which said coil is wound, a plurality of taps to said coil, a second coil located within the first coil and movable with respect to the first coil, a plurality of contact members connected to said taps and to said second coil and secured to said cylinder, and a holder for said coils having a plurality of contact members adapted to make contact with the contact members on the cylinder and thereby serve to hold the coils in a desired position and provide a readily detachable connection between the coils and an electrical circuit.

3. In an apparatus of the class described, the combination of a coil, a hollow cylinder upon which said coil is wound, a plurality of taps to said coil, a plurality of contact members connected to said taps and distributed around the periphery of one end of the cylinder, and a holder for said coil having a plurality of contact members arranged in a circle and adapted to make contact with the contact members on the cylinder and thereby serve to hold the coil in a desired position and provide a readily detachable connection between the coil and an electrical circuit, and means on said holder, cooperating with means on the cylinder for insuring contact between desired contact members when the coil is inserted in the holder.

4. In an apparatus of the class described,

the combination of a coil, a hollow cylinder upon which said coil is wound, a plurality of taps to said coil, a second coil located within the first coil and movable with respect to the first coil, means for rotating said second coil, a plurality of contact members connected to said taps and to said second coil and secured to said cylinder, and a holder for said coils, having a plurality of contact members adapted to make readily detachable contact with the contact members on the cylinder, the means for rotating the second coil being so arranged that at one point in its rotation the second coil will be detached from the means for rotation by the withdrawal of the coils from the holder.

5. In an apparatus of the class described, the combination of a coil, a holder for said coil arranged to hold the coil in a desired position and make electrical connections between the coil and an electric circuit, said coil being arranged so that it can be readily detached from the holder, a second coil mounted within the first and movable with respect to the first coil, a shaft for rotating the second coil, and a connection between the shaft and the coil which may be detached at the same time that the first coil is withdrawn from the holder.

6. In an apparatus of the class described, the combination of a coil, a holder for said coil arranged to hold the coil in a desired position and make electrical connections between the coil and an electric circuit, said coil being arranged so that it can be readily detached from the holder, a second coil mounted within the first and movable with respect to the first coil, a shaft for rotating the second coil, a disk on said shaft having a slot therein and a trunnion on said second coil which is adapted to enter the slot in said disk when the first coil is inserted in the holder and thereby permit of the rotation of the second coil by means of the shaft.

In witness whereof, I have hereunto set my hand this 20th day of July 1922.

RALPH H. Langley.
